(57) **CLAIM**

The ornamental design for an automatic nucleic acid detection analyzer, as shown and described.

DESCRIPTION

1. Automatic nucleic acid detection analyzer

1.1 : Front

1.2 : Back

1.3 : Left

1.4 : Right

1.5 : Top

1.6 : Bottom

1.7 : Front perspective view

1.8 : Back perspective view

The broken lines shown in the drawings illustrate portions of the automatic nucleic acid detection analyzer and form no part of the claimed design.
